US0D1076075S

(12) **United States Design Patent** (10) **Patent No.:** **US D1,076,075 S**
(45) **Date of Patent:** **** May 20, 2025**

(54)	PHARMACEUTICAL PRODUCT CASSETTE FOR AN INJECTION DEVICE	3,064,650 A	11/1962	Lewis
(71)	Applicant: AMGEN INC. , Thousand Oaks, CA (US)	3,203,269 A	8/1965	Perrine
(72)	Inventors: Michael Denzer , Ringoes, NJ (US); Robert W. Swift , Fillmore, CA (US); Neal Johnston , Dallas, TX (US); Gabriele Ganzitti , Milan (IT); Kenneth R. Ewing , Fremont, CA (US); Suhas Krishna , Simi Valley, CA (US)	3,212,685 A	10/1965	Swan et al.
(73)	Assignee: AMGEN INC. , Thousand Oaks, CA (US)	3,297,210 A	1/1967	Lucas
(**)	Term: 15 Years	3,623,474 A	11/1971	Heilman et al.
(21)	Appl. No.: 29/750,216	3,720,211 A	3/1973	Kyrias
(22)	Filed: Sep. 11, 2020	3,859,996 A	1/1975	Mizzy et al.
	Related U.S. Application Data	3,964,481 A	6/1976	Gourlandt et al.
(60)	Division of application No. 29/645,873, filed on Apr. 30, 2018, now Pat. No. Des. 898,908, which is a division of application No. 29/548,508, filed on Dec. 14, 2015, now Pat. No. Des. 819,201, which is a continuation-in-part of application No. 14/112,479, filed as application No. PCT/US2012/034535 on Apr. 20, 2012, now Pat. No. 10,092,706.	4,108,177 A	8/1978	Pistor
(51)	LOC (15) Cl. 24-02	4,198,975 A	4/1980	Haller
(52)	U.S. Cl. USPC D24/127	4,231,368 A	11/1980	Becker
(58)	Field of Classification Search USPC ..... D24/112-114, 108, 133, 130, 127, 186 CPC A61M 5/178; A61M 3/00; A61M 5/20; A61M 5/31; A61M 5/3146; A61M 5/3129; A61M 5/3148; A61M 5/315	4,273,122 A	6/1981	Whitney et al.
	See application file for complete search history.	4,276,879 A	7/1981	Yiournas
